UNITED STATES PATENT OFFICE.

HENRY D. MEDRICK, OF PORT JERVIS, NEW YORK.

FEED-WATER COCK.

SPECIFICATION forming part of Letters Patent No. 402,957, dated May 7, 1889.

Application filed July 25, 1888. Serial No. 281,133. (No model.)

To all whom it may concern:

Be it known that I, HENRY D. MEDRICK, of Port Jervis, in the county of Orange and State of New York, have invented new and useful 5 Improvements in Feed-Water Cocks, of which the following is a full, clear, and exact description.

My invention relates to an improvement in feed-water cocks, and has for its object to 10 provide a cock especially adapted to receive the water in its passage from the tank to the boiler, whereby the water before reaching the boiler will be effectively strained; and the further object of the invention is to provide 15 a straining-cock of simple, durable, and practical construction, and one wherein the sediment may be automatically washed out by the water-supply.

The invention consists in the construction 20 and combination of the several parts, as will be hereinafter fully set forth, and pointed out in the claims.

Reference is to be had to the accompanying drawings, forming a part of this specification, 25 in which similar letters of reference indicate corresponding parts in all the views.

Figure 1 is a central longitudinal section on line $y-y$ of Fig. 2. Fig. 2 is a central vertical section on line $x-x$ of Fig. 1. Fig. 3 is a 30 transverse vertical section on line $z-z$ of Fig. 2, and Fig. 4 is a partial longitudinal section of a modified form.

In carrying out the invention the shell A is 35 preferably made essentially elliptical in general contour, the outer surface whereof may be made square, polygonal, or cylindrical, or semi-cylindrical, if desired.

The extremity a of the shell adapted to approximate the boiler is interiorly threaded to 40 receive any approved form of a coupling-sleeve, a' , or the said sleeve may be swiveled in the said extremity. The opposite extremity, a^2 , of the shell is also interiorly threaded, and in said latter extremity a sleeve, a^3 , is 45 screwed, provided at its outer end with an exterior and interior thread, the exterior thread being adapted to receive the coupling b of the hose B, leading from the tank, and the interior thread a thimble, B' , as best shown 50 in Fig. 1.

At top and bottom of the cock, in the enlarged or central portion, essentially aligning

apertures are respectively produced, the upper aperture being of greater diameter than the lower aperture. In the said apertures a 55 vertical conical casing or plug-seat, d , is secured, preferably extending above and below the shell, or, as illustrated, the plug-seat may be cast an integral portion of the shell. In that face of the plug-seat facing the inlet extremity a^2 an opening, d' , is produced, and upon the outer surface of the plug-seat surrounding said opening a horizontal rib or flange, d^2 , is formed, as best shown in Fig. 2. The rib or flange d^2 is purposed to retain one 65 end of a strainer, E, in engagement with the surface surrounding the opening d' , the other end of said strainer being projected outward to a contact with the thimble B' , whereby the strainer is held rigidly in a horizontal position or parallel with the top and bottom of the shell. 70

The strainer consists of a hollow cylinder of metal or other suitable material having open ends and a series of perforations, e , in 75 the sides.

In the plug-seat d a hollow preferably tapered key, E' , is introduced having an open bottom and a side aperture, e' , adapted, when the plug is properly rotated, to register with 80 the opening d' in the plug-seat, as best shown in Fig. 2.

The plug may be held in place by a washer, nut, or equivalent device secured upon the lower end and rotated by a wrench, crank-arm, or hand-wheel, as in ordinary valves, and, if found desirable, the plug may be provided with an ordinary gland-packing at the upper end. 85

In Fig. 4 I have illustrated a slight modification in the fittings of the water-cock, which is in many instances preferable to the construction set forth in Figs. 1 and 2. 90

The sleeve a^3 is dispensed with, and the thimble B' is provided with an annular exteriorly-threaded flange, h , integral with the inner end, which flange is adapted to abut with the strainer and screw into the body of the cock, the coupling of the hose being adapted to engage with the body of the thimble. 95 By reason of this construction strainers of various diameters may be employed, and the device is simplified. 100

In operation the water, entering through

the strainer at the extremity a^2 of the shell, passes out through the perforations therein around the plug-seat and out through the opposite shell-opening, a , as indicated by arrows 5 in Fig. 1, the plug being so turned that the opening in the plug-seat is closed.

To clean the strainer of the refuse matter, the side aperture in the plug is made to register with the opening in the plug-casing, as 10 shown in Fig. 2. The water now passing directly through the strainer passes into the plug, carrying the dirt before it, and out through the bottom of said plug.

It will be observed that as the water constantly surrounds the plug-seat the plug is 15 not liable to be frozen up in cold weather.

Having thus described my invention, I claim as new and desire to secure by Letters Patent—

1. The combination, with a shell having a 20 longitudinally-extending strainer-tube at its inlet end, of a transverse valve-seat in the shell having a side or lateral opening into which the inner end of the strainer leads, and a cock having an open bottom or end and a 25 side opening to register with that of the seat, whereby when the said openings register the water will flow longitudinally through the strainer and out through the cock, and when the cock closes the seat-opening the water will 30 flow laterally through the strainer and through the shell, substantially as set forth.

2. The combination, with the shell having its sides outwardly bowed near the center

and a vertical plug-seat secured in said shell between the curved sides, provided with an 35 inlet-opening, of a horizontal perforated straining-tube connected with the inlet of the shell and the inlet of the plug-seat, and a hollow plug provided with an inlet in the side and an exit-opening in the bottom, substantially 40 as shown and described.

3. The combination, with an essentially elliptical shell and a tapering plug-seat extending vertically through the shell from top to bottom and provided with an inlet-aperture, 45 of a tubular perforated strainer attached to the plug-seat around the aperture therein and to the inlet extremity of the shell, and a hollow plug provided with an inlet in the side and an outlet in the bottom, substantially 50 as shown and described.

4. The combination, with an essentially elliptical shell, a tapering plug-seat extending vertically through the shell from top to bottom, provided with an inlet-aperture in 55 the side, of a tubular perforated strainer attached to the plug-seat around the aperture therein, a hollow plug provided with a side inlet and a bottom outlet, and a thimble abutting with the outer end of the strainer, substantially 60 as shown and described.

HENRY D. MEDRICK.
